UNITED STATES PATENT OFFICE.

WILLIAM H. PARDEE AND FENTON E. JUDSON, OF ANTIGO, WISCONSIN.

DESIGN FOR A LACE-FASTENER.

SPECIFICATION forming part of Design No. 30,652, dated May 2, 1899.

Application filed April 10, 1899. Serial No. 712,545. Term of patent 14 years.

To all whom it may concern:

Be it known that we, WILLIAM H. PARDEE and FENTON E. JUDSON, residing at Antigo, in the county of Langlade and State of Wisconsin, have invented and produced a new and original Design for a Lace-Fastener, of which the following is a specification, reference being had to the accompanying drawings, forming a part thereof, in which similar characters of reference indicate corresponding parts in both views.

Figure 1 is a top plan view of a lace-fastener embodying our design, and Fig. 2 is a side elevation thereof.

The design in its entirety comprises two elements A and B. The element A is shaped to produce the appearance of a circular eye, and the element B is carried by the element A and has a twisted conformation, producing the appearance of a peculiar hook, arched from the eye, with a lateral trend at said arched portion, the end beyond the arch ranging downwardly and inwardly and then upwardly to give the free end a lateral trend in

a direction opposite the lateral trend at the arch.

The design further comprises that configuration of the hook which presents the appearance of the inner portion or shank provided with a concavo-convex form which vanishes toward the point of the hook and the hook terminating at this point in a plane flat portion, all as shown in the drawings.

The leading feature of the design consists in the lace-fastener having the hook arched from the eye with a lateral trend at said arched portion, the end beyond the arch running downwardly and inwardly and then outwardly to give the free end a lateral trend in a direction opposite the lateral trend at the arch.

We claim—

The design for a lace-fastener, herein shown and described.

WILLIAM H. PARDEE.
FENTON E. JUDSON.
